UNITED STATES PATENT OFFICE.

EDMUND HOFFMAN, OF BROOKLYN, NEW YORK, ASSIGNOR TO AMERICAN CAN COMPANY, OF NEW YORK, N. Y., A CORPORATION OF NEW JERSEY.

DESIGN FOR A BOX FOR TALCUM POWDER.

47,134.

Specification for Design.

Patented Mar. 23, 1915.

Application filed October 7, 1914. Serial No. 865,599. Term of patent 7 years.

To all whom it may concern:

Be it known that I, EDMUND HOFFMAN, a citizen of the United States, residing at Brooklyn, in the county of Kings and State of New York, have invented a new, original, and ornamental Design for Boxes for Talcum Powder, of which the following is a specification, reference being had to the accompanying drawing, forming a part thereof.

On the drawing, Figure 1 is a side elevation of a box constructed in accordance with my invention. Fig. 2 is a top plan view of same, and Fig. 3 a perspective view.

The design is characterized by a body square in cross section, with rounded cor-

ners, which body has a pronounced taper from an enlarged top to a relatively small bottom. The upper end of this body is bounded by a peripheral bead, above which the sides are vertical for a short distance. In the middle of the enlarged top is a cylindrical neck surmounted by a circular cap.

I claim:

The ornamental design for a box for talcum powder, as shown and described.

EDMUND HOFFMAN.
